UNITED STATES PATENT OFFICE.

CONRAD VAUGHAN, OF HANDSWORTH, BIRMINGHAM, ENGLAND.

MANUFACTURE OF DIE CASTINGS.

Application filed October 22, 1927, Serial No. 228,040, and in Great Britain September 10, 1927.

This invention relates to the manufacture of die castings and although applicable to die castings generally is particularly intended for application to pressure die castings.

In connection with die castings generally and particularly with pressure die castings it is well known that such castings are particularly subject to blow holes in the interior, especially in the thicker portions of such castings.

It is believed that these blow holes are formed by the air which is in the die before the metal enters, such air being unable to leave the die and consequently forming pockets in the interior of the casting.

The object of the present invention is to provide certain improvements whereby this defect can be overcome.

According to the present invention the die is formed with one or more expanding chambers, such chambers being provided particularly where the thicker parts of the metal are to be formed, the arrangement being such that prior to the metal entering the die, such chambers are collapsed or partially collapsed so that the amount of air at such positions is much reduced and the chamber or chambers expanding as the metal runs into the die.

The expanding die or the expanding portion of the die may be formed by providing movable portions of piston like or plunger like form in the die at those positions where the metal in the finished casting is to be thickest, the piston like or plunger like portions moving outwardly as the metal enters the portions of the die where they are situated.

The piston like or plunger like portions may be moved outwardly by the pressure of the incoming molten metal and such outward movement may take place against a suitable resistance which may be provided by a dash pot or a spring or similar device.

Referring to the drawings:—

Figure 1 is a view in section illustrating a simple form of my invention.

Figure 2 is a view in section showing another application of my invention.

Figure 3 is a sectional view showing a third method of application of the invention.

Referring to Figure 1, the die 1 is provided with a piston like member 2 forming a movable side to the die.

The usual opening is provided at 3 for the nozzle through which the incoming metal is forced.

The piston like portion 2 is provided with a rod 22 having a collar 4 against which acts a strong spring 5 supported by a suitable abutment 6.

In such a die assuming that the piston 2 is not provided, when the metal is forced through the nozzle the air in the die is unable to escape and the incoming metal tends to flow round the walls of the cavity within the die so that the air is eventually enclosed in the finished casting, which is thus hollow or very porous.

In the apparatus illustrated, however, the amount of air in the die before the entrance of the molten metal is reduced to a negligible quantity, such air being contained only in the space 7.

As the metal enters the pressure thereof drives back the piston 2 until its rear wall 8 meets the part 9 of the die, and it is found that a non-porous casting which is free from blow holes can thus be produced.

If required a suitable outlet may be provided for the air which is present behind the piston before the metal is introduced.

In the arrangement shown in Figure 2 the casting to be produced is of substantially constant thickness except for a portion to be produced at 10, and this portion is provided with a plunger like member 11 so that the air in the portion 10 is much reduced at the start.

Upon the metal entering through the nozzle which is fixed in the opening 12, it flows into the cavity of the die and drives back the plunger 11 which is fitted with a dash pot appliance 13 until the whole of the cavity 10 becomes filled with metal.

If required, the dash pot device may be provided with a valve of any suitable or well known construction so that the resistance offered thereby can be adjusted.

In the arrangement shown in Figure 3 the die 14 is shaped for producing a casting consisting of a bar portion 15 having a number of lumps or projecting pieces 16 thereon.

Normally the lumps or projecting pieces 16 would be found to be porous or to contain serious blow holes and according to the present invention each of the portions 16 is provided with a piston like member 17, and the rods 18 attached to the piston like parts 17 may be all connected together by a transverse 110

bar 19 which has a rod 20 to which a spring or dash pot resistance is applied.

In this construction the metal projecting nozzle is fixed in the opening 21 and as the metal enters the die the piston like portions 5 17 are driven back by the pressure thereof.

What I claim then is:—

1. Apparatus for the manufacture of die castings comprising a mold, and a fluid actuated plunger within said mold adapted to 10 recede therein under the action of the fluid entering the mold.

2. Apparatus for the manufacture of die castings comprising a mold, a plunger disposed within that part of the mold where the finished casting is to be thickest, and means 15 for controlling the movement of said plunger.

3. Apparatus for the manufacture of die castings comprising a mold having a recess in 20 its inner wall, a fluid actuated plunger adapted to work in said recess and to recede therein under the action of the fluid entering the

mold, and means for controlling the movement of said plunger.

4. Apparatus for the manufacture of die 25 castings comprising a mold having a recess in its inner wall at that part where the finished casting is to be thickest, a fluid actuated plunger adapted to work in said recess and to recede therein under the action of the fluid 30 entering the mold, and hydraulic dash pot means adapted to control the movement of the said plunger.

5. Apparatus for the manufacture of die 35 castings comprising a mold, a plunger projecting into said mold at one side of the same to displace certain of the air content thereof, and means for admitting molten metal to the interior of the mold, said plunger being adapted to recede outwardly of the mold under the action thereon of the incoming metal. 40

In witness whereof I affix my signature.

CONRAD VAUGHAN.
